UNITED STATES PATENT OFFICE

RALPH E. MCKENZIE, OF LA CROSSE, WISCONSIN, ASSIGNOR, BY MESNE ASSIGNMENTS,
TO OLIVER FARM EQUIPMENT COMPANY, A CORPORATION OF DELAWARE

SPRAYING APPARATUS

Application filed April 29, 1929. Serial No. 358,811.

This invention relates to spraying apparatus and more particularly to a novel form of suction well associated and combined with such an apparatus in a manner to overcome certain difficulties hereinafter pointed out.

An object of my invention is to provide a device of the kind above identified which is adapted to prevent the accumulation of sediment in the suction well and on the screens thereof, especially when the spraying operation is temporarily discontinued.

Another object is to provide a suction well having a compartment into which the suction pipe extends and having a chamber thereabout adapted to receive the overflow or excess of fluid and return it to the space surrounding the suction compartment in such a manner as to keep the screens of the well cleaned and to maintain a constant agitation of the fluid, retaining the solid substances in suspension and preventing the collection of sediment.

The material used for spraying purposes ordinarily contains a large proportion of solids and unless the fluid is constantly agitated for the purpose of keeping the solids in suspension, they will settle forming a sediment and clogging the screen employed at the intake end of the suction pipe. To avoid the loss of spraying fluid, it is customary to shut off the discharge valve when reaching the ends of the rows of potatoes, or the like, which are being sprayed, and again open the discharge valve when starting to spray another set of rows. When the valve is thus temporarily closed, the movement of the fluid is stopped and the solids in suspension will gravitate forming a sediment in the suction well and on the screen. When the valve is again opened the screen is partially filled with sediment and the passage of fluid therethrough is difficult. If the fluid is again set in motion it frequently carries with it a sufficient quantity of the sediment to clog up the spray nozzle.

By my invention I have provided an apparatus so arranged that the screens in the suction well do not readily become clogged. If for any reason the screens should become clogged, the arrangement of my invention is

such that automatic cleaning of the screens may be readily effected.

My invention will be best understood by reference to the accompanying drawings which illustrate one specific embodiment thereof.

Fig. 1 is a vertical section of a spraying apparatus incorporating my invention, parts being broken away to more clearly illustrate the interior thereof and the mode of operation.

Fig. 2 is a vertical section of my improved suction well.

Fig. 3 is a cross-section taken on the line 3—3 of Fig. 2.

In Fig. 1 the spraying apparatus comprises a base member 4 suitably supported by traction wheels 5, one of which is shown in the sectional view. The tank 6 of any suitable construction is adapted to contain the spraying fluid. A suction pipe 7 leads from the suction well 8 in the bottom of tank 6 upwardly through a suitable cover 7'. To the end of pipe 7 is connected a flexible tube 9 leading to the pump 11 which is driven from the sprocket wheel 13 by means of a chain 12. The sprocket wheel 13 is arranged to rotate with one of the traction wheels 5 and impart reciprocating motion to the piston rod 12' whenever the traction wheels are rotated.

The chain 12 also rotates a sprocket 15 for the agitator 16, the purpose of which is to maintain a constant agitation of the fluid in the bottom of the tank 6. An air chamber 17 connecting with the discharge side of the pump 11 by means of a pipe 11' is adapted to receive and discharge fluid through the pipe 11' so as to keep a relatively constant pressure within the pipe 18 leading to the spray nozzle 22. A discharge valve 19 in the pipe line 18 may be opened and closed by a hand wheel 23 located just above the top of tank 6 in a position convenient for the operator. When the valve 19 is open, spraying fluid is free to pass therethrough, through the hinge joint 21 and out the spray nozzle 22.

The pump 11 is made of such a size that it pumps considerably more fluid than can be discharged through the spray nozzle. The excess of fluid from the pump passes into the

chamber 17, then outwardly through the bypass valve 24 when a predetermined pressure has been attained. From the valve 24 the fluid is returned through the hose 25 to the suction well 8. The suction well comprises a bell shaped top casting 26 seated on a disc 27. A disc 28 is secured in spaced relation to the disc 27 by bolts 31 passing therethrough, and by spacers 29 and 29'. Annular flanges 32 on the discs 27 and 28 form supports for a screen 33 of relatively fine mesh which encloses the end of suction pipe 7 forming a suction compartment. A baffle 34 formed integral with the disc 28 extends across the suction compartment and perpendicular to the end of the suction pipe 7 in such a manner as to prevent whirling of the spraying liquid as it passes into the pipe. The baffle 34 also forms an abutment for the suction pipe 7.

20 Annular flanges 35 support the screen 36 concentrically about screen 33 forming a return compartment. The fluid returning through hose 25 discharging into chamber 20 may find its way, through the apertures 38 in the disc 27 between flanges 32' and 35, into this return compartment. The casting 26 has a nipple 39 onto which the return hose 25 is fitted.

In the operation of the apparatus, rotation 30 of the traction wheels 5 operates the pump 11, which draws fluid from the suction well 8 through pipe 7 and tube 9, discharging it into pipe 18 and air chamber 17 through pipe 11'. When the valve 19 is opened, fluid will 35 spray through the nozzle 22.

Since the pump forces more fluid into the chamber 17 than can be discharged through nozzle 22, a sufficient pressure builds up to open the by-pass valve 24 and permit the excess fluid to return through hose 25 into the fluid return chamber 20. From the chamber 20 the excess fluid passes downwardly through the openings 38 in the disc 27 in a direction substantially parallel with the 40 screens 33 and 36, thereby removing sediment which may have collected on the screens. When the valve 19 is closed the pump continues to spray and all the fluid drawn through the suction pipe is returned through 50 the hose 25 to the chamber 20 in the suction well. The fluid is constantly drawn through the screen 33 at a relatively high rate of speed. Consequently the solid materials therein are kept constantly in suspension and no sediment is permitted to form. When the valve 55 19 is again opened the spraying operation is immediately continued without such difficulties, as a clogged screen or a spray nozzle filled with a large quantity of sediment.

60 If for any reason the screens should become partially clogged, they may be automatically cleaned by simply closing the valve 19 for a brief period and allowing all the fluid from the pump to return downwardly 65 through the openings 38 in a direction paral-

lel with the screens which very quickly removes the sediment therefrom.

Having described my invention, it will be understood by those skilled in the art that certain changes and variations may be made 70 therein without departing from the spirit and scope of the appended claims.

I claim as my invention:

1. In a spraying apparatus, a tank for a spraying solution, means for conveying the 75 solution from the tank including a suction pipe, a screen enclosing the end of the suction pipe, a second screen surrounding the first screen leaving a space between the screens, and means for returning a portion of the solution to the space between the screens to keep 80 the solution in said space in constant agitation.

2. In a spraying apparatus, a container for a spraying solution, means for withdrawing the solution from the container including a pipe extending into the solution, means for drawing the solution through said pipe, a plurality of spaced screens surrounding the 85 end of the pipe, and means for keeping the 90 solution agitated in the space between the screens.

3. In a spraying apparatus, a suction well comprising a pipe for discharging a liquid, a screen enclosing the end of the discharge 95 pipe, a second screen surrounding the first screen leaving a space therebetween, a chamber communicating with the space between the screens and means for conveying a portion of the discharged solution through said 100 chamber into the space between the screens to prevent the formation of sediment.

4. The combination of a liquid container, a pump for withdrawing liquid from the container, a suction well connected to the 105 pump and located in the container, a screen in said suction well, means for returning a portion of the liquid withdrawn by the pump to the suction well, and means for causing the returned liquid to move perpendicularly to the liquid passing through the screen, thereby 110 preventing the accumulation of sediment.

5. In a spraying apparatus an intake strainer comprising a pair of spaced discs, a pair of concentric cylindrical screens of different diameters between said discs, an intake pipe extending into the smaller cylindrical screen, and a return pipe communicating with the space between the screens.

6. A suction well comprising means for receiving discharge pipe, said means including a fluid return chamber, a suction chamber below said fluid return chamber, said suction chamber comprising a suction compartment and a fluid return compartment, a screen between said compartments and means for permitting the passage of fluid from said return chamber into said return compartment in a direction substantially parallel with said screen.

7. In a suction well, means for receiving a discharge pipe, a suction chamber, screens dividing said chamber into a plurality of compartments, a return chamber communicating with one of said compartments and another of said compartments communicating with the discharge pipe.

8. In a suction well, a suction chamber and a fluid return chamber, a disc member for separating said chamber, a second disc spaced from the first said disc and forming the bottom of said suction chamber, screen supporting flanges on said disc, screens dividing said suction chamber into a plurality of concentrically arranged cylindrical compartments, means for admitting the discharge pipe into the inner cylindrical compartments and means for directing fluid from return chamber to the outer cylindrical compartment in a direction parallel with said screens.

9. In a suction well, a suction chamber and a fluid return chamber, a disc member for separating said chamber, a second disc spaced from the first said disc and forming the bottom of said suction chamber, screen supporting flanges on said discs, screens engaging said flanges and dividing said suction chamber into a plurality of concentrically arranged compartments, means for admitting the end of a discharge pipe into the inner compartment, a baffle plate in said inner compartment for dividing the lower end thereof and preventing the whirling of fluid in said pipe, and means for directing fluid from the return chamber to the outer compartment in a direction substantially parallel with said screens.

10. A spraying device comprising an intake compartment, two spaced apart intake screens arranged anteriorly thereof, a liquid supply tank communicating with the compartment through the screens, a pump communicating on its intake side with said chamber, a spray nozzle communicating with the discharge side of the pump, and means for withdrawing, anteriorly of the nozzle, a portion of the liquid pumped by the pump and for returning it to said chamber between the screens.

In witness whereof, I hereunto subscribe my name this 22d day of April, 1929.

RALPH E. MCKENZIE.
